UNITED STATES PATENT OFFICE.

EDWARD J. DOTY, OF BALTIMORE, MARYLAND, ASSIGNOR TO SIEGEL, ROTHSCHILD & CO., OF BALTIMORE, MARYLAND.

DESIGN FOR AN UMBRELLA.

Application filed January 10, 1925. Serial No. 11,991. Term of patent 3½ years.

To all whom it may concern:

Be it known that I, EDWARD J. DOTY, a citizen of the United States, residing at Baltimore, State of Maryland, have invented a new, original, and ornamental Design for an Umbrella, of which the following is a specification, reference being had to the accompanying drawing, forming a part thereof.

I claim:

The ornamental design for an umbrella, as shown.

EDWARD J. DOTY.
